UNITED STATES PATENT OFFICE.

WARD W. WILLITS AND ANTHONY M. DUBURN, OF CHICAGO, ILLINOIS,
ASSIGNORS TO THE ADAMS & WESTLAKE MANUFACTURING COMPANY
OF MICHIGAN, OF SAME PLACE.

CANOPY FOR RAILWAY-CAR LAMPS.

SPECIFICATION forming part of Letters Patent No. 364,154, dated May 31, 1887.

Application filed December 27, 1886. Serial No. 222,623. (No model.)

To all whom it may concern:

Be it known that we, WARD W. WILLITS and ANTHONY M. DUBURN, both of Chicago, in the county of Cook and State of Illinois, have invented certain new and useful Improvements 5 in Canopies for Railway-Car Lamps, of which the following is a specification, reference being had to the accompanying drawings and to the letters of reference marked thereon.

Our invention is designed more especially for use with a center lamp having a burner which produces a powerful flame of intense heat, the object of the invention being to provide a canopy for such a lamp which shall be thoroughly 10 ventilated and cooled by the passage of air through it, and which, in connection with the exterior ventilator, shall assist in the ventilation of the car.

In the accompanying drawings, Figure 1 is 20 a perspective view representing our invention as applied to a car-roof, and also showing the relation existing between the canopy and the lamp and exterior ventilator. Fig. 2 is a vertical longitudinal section through the canopy, 25 car-roof, and exterior ventilator.

Similar letters of reference indicate like parts in the respective figures.

A represents the roof of the car, B the canopy, and C the exterior ventilator. 30 The top flange, a, of the rim or support B' is secured to the car-roof, as shown, and immediately below the flange a the rim B' is provided with a series of perforations, b.

The canopy proper or lower bell, B, is constructed of an outer shell, c, and an inner shell, c', a space, c'', being left between the two shells. The inner shell, c', is swaged upon the upper part or neck, D, of the outer shell, c, at d, while the rim B' is attached to the section D in any 40 suitable manner. The section D need not necessarily be integral with the outer shell. The section D is provided at its upper end with holes e, which communicate with the space c'' between the inner and outer shells. The section D is provided with a top flange or shoulder, f, between which and the top edge of the inner shell, c', is swaged or otherwise attached the metallic chimney E, the lower part of which registers with the opening at the top of the inner shell, c.

Referring to the exterior ventilator, C, G is a cylinder, the lower flange, g, of which is secured to the roof A of the car. F is a tapered tube which fits over the top of the section D, and H is an outer hood or cap secured to the tube F by standards h. The upper part of the tapered tube F is provided with holes i. The canopy and ventilator being in place, as shown in the figures, the heat from the flame passes directly through the metallic chimney E, and thence through the hood or cap H to the outer air.

If the canopy were constructed of but a single shell, the intense heat of the lamp for which this invention is designed would be liable to 65 set fire to the wood-work of the car; but, air being admitted into the space c'' and openings b, the lower bell or canopy and the rim B' are kept comparatively cool. At the same time the canopy serves as an effective ventilator. 70 The tapered tube F, fitting over the upper part of the section D, serves to confine the heat within the canopy and exterior ventilator, and prevent it coming in contact with the wood-work of the car. It will be seen that while 75 there is no communication between the interior of the bells and the wood-work, there is direct communication between the interior of the car and the ventilator through the openings b and between the canopy and the interior of the 80 ventilator through the openings e in the upper part of the section D.

We do not limit ourselves to the mode of connecting the parts of the canopy and rim or support B', provided that such a construction 85 be adopted as will produce a double or two-shell lower bell with passages, substantially as hereinbefore described; neither do we restrict ourselves to the particular construction of exterior ventilator, provided it shall perform the 90 functions hereinbefore described—that is to say, shall aid in excluding heat from the wood-work of the car and permit a free escape of vitiated air from the car through openings in a part of the canopy or its support.

We are aware that it is not new to make the smoke-jack of a lamp of concentric tubes and to combine the same with the roof of a car and an outer ventilator, and such construction we broadly disclaim; but,

Having described our invention, what we claim is—

1. A canopy or lower bell, B, consisting of the outer shell, c, and the inner shell, c', united or swaged together, a space, c², being formed between the shells, and the upper part of the outer shell, c, being provided with perforations e, combined with the rim or support B', having the perforations b, substantially as set forth.
- 10 2. The two-shell lower bell or canopy, B, having the space c² and perforations e, combined with the ventilated rim or support B', the chimney E, leading to the interior of the inner shell of the canopy, and the tube F, forming with the chimney E a space communicating by means of the perforations e with the space c², substantially as set forth.

3. The two-shell lower bell or canopy, B, having the space c² and perforations e, combined with the ventilated rim or support B', the chimney E, leading to the interior of the inner shell of said canopy, the tube F, forming with the chimney E a space communicating by means of the perforations e with the space c², the cylinder G, surrounding that part of the tube F which is exterior of the car, and the hood H, substantially as set forth. 20 25

In testimony whereof we hereunto set our hands and seals.
